UNITED STATES PATENT OFFICE

AUGUST C. BRILL, OF OBERURSEL, NEAR FRANKFORT-ON-THE-MAIN, GERMANY, AS
SIGNOR TO THE TURNER TANNING MACHINERY COMPANY, OF PORTLAND, MAINE,
A CORPORATION OF MAINE

CHEEKING MACHINE

Application filed January 7, 1928, Serial No. 245,222, and in Germany January 11, 1927.

This invention relates to cutting machines and is illustrated as embodied in a cheeking machine for reducing the thickness of portions of hides and skins over certain areas as, for example, the head and neck portions of calf skins, although in various respects the invention is not limited to machines for performing such operations.

Cheeking machines have customarily been provided with cutters movable in a direction transverse of that of the feeding movement of the work to produce a drawing cut, with bed rolls to support the work during the operation of the cutters, and with presser members for holding the work against the bed rolls. While these machines operate efficiently when the cutters are kept in sharpened condition and the work is properly conditioned before being presented to the machines, it has been found that as the cutter becomes dull or if the work is too hard, the work has a troublesome tendency to move sidewise with the cutter.

It is accordingly an object of this invention to provide improved means for insuring that the work will not follow the cutter during reciprocations of the latter transverse to the direction of feeding movement of the work, even if the cutter be allowed to become somewhat dull, or if the work due to improper conditioning thereof should present hard spots to the cutter.

This object is conveniently accomplished, in the illustrated machine, by providing means for pressing the pieces of work against a work support wherein the pressing means comprises a presser member having on its work engaging face one or more sharp edges provided by grooves or ribs extending substantially at a right angle to the path of movement of the cutter. As illustrated, a plurality of presser plates are arranged in side by side relationship and each is provided with a concave surface to co-operate with a bed roll throughout the whole work supporting length of the latter, the concave surface of each presser plate having a plurality of grooves all parallel and extending in directions at right angles to the path of movement of a reciprocating cutter, the grooves of all of the presser

plates combined being so numerous as to engage with such a multiplicity of closely spaced portions of the work throughout the whole width thereof as to hold every portion thereof against lateral movement during the reciprocatory drawing cut of the cutter.

These and other features of the invention and novel combinations of parts will now be described in detail and pointed out in the appended claims.

In the drawings,

Fig. 1 is a rear elevational view of a cheeking machine showing one embodiment of the invention;

Fig. 2 is a view of the essential elements of the machine taken along the line II—II in Fig. 1;

Fig. 3 is a view of the work engaging face of one of the presser members; and

Fig. 4 is a vertical, transverse section of the presser member shown in Fig. 3.

In the illustrated cheeking machine a piece of work such as a hide or skin is supported for the operation of a cutter 8 by means of a bed roll 10. For co-operation with the bed roll in feeding the work to the cutter there is provided a feed roll 12, the latter being preferably covered with a tightly fitted rubber sleeve 13 for frictionally and yieldingly engaging the work. In order that a piece of work may be readily introduced into the feeding means comprising the two rolls 10 and 12, the roll 10 is mounted rotatably in the upper ends of two arms 14, each arm being pivoted at 16 to a frame member 18 and having at its lower end a pivot pin 20 for connection with an operating pitman (not shown). When the pitman is reciprocated the arms 14 are rocked about the pivot 16 to move the bed roll 10 first to work receiving position away from the cutter 8 and feed roll 12. Upon movement of the arms 14 in the opposite direction, the bed roll 10 is moved into co-operative relation with respect to the feed roll 12 and presents a portion of the work 22 to the cutter 8, as most clearly disclosed in Fig. 2 of the drawings. As soon as the bed roll 10 reaches work presenting position with respect to the cutter 8 it begins to rotate in the direction of the arrow (Fig. 2),

being driven by a pinion 24 on shaft 26 of the bed roll in engagement with a pinion 28 on shaft 30 of the feed roll 12. Shaft 30 is stationary in space, being mounted within the side frames 18 of the machine and is power driven from a gear wheel 32 operated by connections (not shown) with a suitable source of power. As soon as the bed roll 10 reaches work presenting position with respect to the cutter 8 the latter begins to reciprocate, lengthwise of the bed roll and parallel to the axis of the work supporting surface thereof, so as to cut through the piece of work with a drawing cut designed to secure more uniform and effective cutting of the work than is ordinarily accomplished by a stationary knife. The cutter 8 is mounted upon a reciprocable bar 38 adapted to slide in guideways provided by suitably shaped recesses in the standards or frame members 18. While any suitable arrangement may be provided for reciprocating the bar 38, that shown comprises a pitman 40 pivoted at 42 to the bar 38 and its other end pivoted eccentrically to a wheel 44 secured upon a shaft 46 arranged to be driven from any suitable source of power.

In order to prevent the piece of work from following the reciprocations of the cutter, there are provided presser members 50 each mounted upon its own individual holder 52, the lower ends of the holders 52 being secured to a bar 54 which extends from the frame member or standard 18 at one end of the machine to the corresponding frame member or standard 18 at the other end of the machine. It will be observed upon inspection of Figs. 2 and 4, that each presser member 50 has a concave surface 56 for engaging the work so as to press the latter into close contact with the correspondingly convexly shaped surface of the bed roll 10. Furthermore, the concave surface 56 is provided with a number of grooves 58 parallel to each other and parallel also to the direction of feeding movement of the work, the purpose of the grooves being to guide the work in the feeding direction and to maintain it against lateral movement which might otherwise take place by reason of friction between the cutter and the work as the former reciprocates transversely of the path of the work during cutting operations. Preferably and as shown, the grooves 58 have rather sharp edges 57 so as to engage the work more effectively than would otherwise be the case. As will be observed from an inspection of Fig. 4 the spaced parallel grooves 58 provide ribs 59 parallel with the grooves. Although the ribs thus formed do not project above the surface 56, it is clear that the ribs with sharp edges 57 may be regarded as the guiding means. From another viewpoint the grooves serve as the guiding means since the substance of the hide or skin will engage therein, due to the pressure exerted through the resilient holders 52. It will be noticed further, upon inspection of Fig. 3, that each presser member 50 is provided with many closely spaced grooves each having two sharp edges 57. Since the presser members extend in side-by-side relationship clear across the length of the work-supporting surface of the bed roll 10, the sharp edges 57 are so numerous as to engage with such a multitude of closely spaced portions of the piece of work throughout the whole width of the latter as to hold every portion of the work against lateral movement due to a tendency to follow the reciprocatory cutter during the operations of the latter. Upon inspection of Fig. 2 it will be observed that the upper ends of the presser members 50 extend closely to and slightly overlap the plane of the cutting edge of the cutter 8 so as to guide the work and control it while the very end portion of the latter is being operated on, thus insuring a clean cut to the very end of the piece of work.

In operating with the machine illustrated in the drawings, the operator will introduce a piece of work over the bed roll 10 while the latter is in work receiving position, that is, to the left of the position of the bed roll in Fig. 2. For the proper operation of the machine it is necessary that the head and neck portions of the hide or skin be thrown over the bed roll 10 so that upon movement of the latter to work presenting position with respect to the cutter 8, these portions of the hide or skin will be located below the cutter. When the bed roll 10 moves to work presenting position the knife 8 begins to reciprocate and the feed rolls 10 and 12 begin to rotate so that the cutter will operate to split a portion 60 from the head and neck portions of the hide or skin thereby reducing these portions to substantially the thickness of the body portion of the hide or skin. To accomplish this, it is obvious that the cutter 8 and bed roll 10 should be relatively adjustable by means not shown so that in their work operating positions the cutter will remove an excess thickness just sufficient to even the head and neck portions with the rest of the hide or skin. While the feed rolls 10 and 12 rotate to feed the work past the cutter, the members 50 serve as pressing and guiding members for the work and particularly as means for preventing the work from following the reciprocations of the cutter.

Having described my invention, what I claim as new and desire to secure by Letters Patent of the United States is:

1. In a cutting machine, a work support, means for feeding a piece of work over the work support, a cutter movable in a direction transverse of the path of the work for operating on the work while it is backed by the work support, and means for pressing the work against the work support to prevent lateral movement of the work during the cutting operation.

eral movement of the work during movement of the cutter in a direction transverse of the moving work, said means comprising a member having a plurality of sharp edges extending in a direction at a right angle to the cutter.

5 2. In a cutting machine, a work support, means for feeding a piece of work over the work support, a movable cutter for operating on the work while it is backed by the work support, and a plurality of members for pressing the work against the work support to maintain it against lateral movement during movement of the cutter, each member having a sharp edge extending in a direction at a right angle to the path of movement of the cutter.

10 3. In a cutting machine, a work support, means for feeding a piece of work over the work support, a movable cutter for operating on the work while it is backed by the work support, and a plurality of members each having a plurality of grooves extending all in the same direction at a right angle to the cutter to prevent movement of the work in a direction transverse of its feeding movement.

15 4. In a cheecking machine, a work support for supporting a piece of work while it is undergoing cutting operations, means co-operating with the work support to feed the piece of work, a cutter movable in a drawing cut in a direction lengthwise of the work support to split a piece of work while it is backed by the support, and means comprising a plurality of presser members for pressing the work upon the work support, each presser member having a plurality of sharp edges extending in a direction at a right angle to the cutter to prevent lateral movement of the work while the cutter is moving in a direction lengthwise of the bed roll.

20 5. In a cheecking machine, a bed roll for supporting a piece of work while it is undergoing cutting operations, means co-operating with the bed roll to feed the piece of work, a cutter movable in a direction lengthwise of the bed roll and laterally of a piece of work on the bed roll to split the work while it is backed by the bed roll, and a plurality of presser members for co-operation with the bed roll to guide the work, each presser member having a groove extending in a direction substantially at a right angle to the path of movement of the cutter and operative to prevent movement of the work with the cutter as the latter moves laterally of the work.

25 6. In a cheecking machine having a bed roll for supporting a piece of work during cutting operations, a roll for co-operating with the bed roll in feeding the work and a reciprocable cutter movable in a path parallel to the axis of the supporting surface of the bed roll, means for pressing the work against the bed roll and operative to prevent the work from following the cutter during reciprocation thereof, said means comprising a presser

member having a plurality of ribs extending in a direction at a right angle to the path of the cutter.

7. In a cheecking machine, a bed roll for supporting a piece of work during cutting operations, a roll for cooperating with the bed roll in feeding the work, a reciprocable cutter movable in a path parallel to the axis of the supporting surface of the bed roll, and a plurality of members for pressing the work against the bed roll, said members operating to guide the work and having grooves which are parallel with each other throughout the whole of the work-supporting length of the bed roll and extend in a direction substantially at a right angle to the path of the cutter.

8. In a cheecking machine, a bed roll for supporting a piece of work during cutting operations, a roll for cooperating with the bed roll in feeding the work, a reciprocable cutter movable in a path parallel to the axis of the supporting surface of the bed roll, and a plurality of members for pressing the work against the bed roll, each presser member having its work engaging face provided with a sharp-edged groove extending substantially at a right angle to the path of reciprocation of the cutter.

9. A cheecking machine having, in combination, a support for a hide or skin, a member for engaging a hide or skin on the support to effect a feeding movement of the hide or skin, a cutter operable transversely of the direction of feeding movement of the hide or skin and constructed and arranged to split portions from the hide or skin, means for operating the cutter, and means for pressing the hide or skin against the support, said means comprising a plurality of presser members extending across the length of the work supporting surface of the support in side-by-side relationship, and said presser members having a multiplicity of sharp edges extending in a direction at a right angle to the path of the cutter and operative to engage a hide or skin in a multitude of places to prevent the latter from moving with the cutter transversely of the direction of feeding movement of the hide or skin.

10. In a cheecking machine, a bed roll for supporting a piece of work during cutting operations, a roll for co-operating with the bed roll in feeding the work, a reciprocable cutter movable in a path parallel to the axis of the supporting surface of the bed roll, and a plurality of members for pressing the work against the bed roll to guide it to the cutter, each presser member having a concave work engaging surface provided with a multiplicity of sharp-edged grooves extending in a direction substantially at a right angle to the path of movement of the reciprocable cutter, the sharp edges of the grooves being so numerous as to engage with a multitude of close-

ly spaced portions of the piece of work throughout the width of the latter to prevent movement of any portion of the work with the reciprocable cutter.

11. A checking machine having, in combination, a support for a hide or skin, a member for engaging a hide or skin on the support to effect a feeding movement of the hide or skin, a cutter operable in a direction substantially at a right angle to the direction of feeding movement of the hide or skin and constructed and arranged to split portions from the hide or skin, means for operating the cutter, and means for pressing the hide or skin against the support and for guiding the hide or skin to the extreme rear edge portion thereof to the cutter, said last-named means comprising presser members having sharp edges extending in a direction at a right angle to the path of the cutter to hold the hide or skin from following the cutter, the presser members being arranged slightly to overlap the cutter to control the hide or skin so that it is cut to the very end thereof.
12. In testimony whereof I have signed my name to this specification.

AUGUST C. BRILL.
